Application April 23, 1937, Serial No. 138,518

4 Claims. (Cl. 72—40)

The present application is a continuation in part of co-pending application Serial No. 702,008.

The present invention relates to building constructions embodying precast slabs of set cementitious material.

The principal object of the invention is the provision of a building construction embodying such slabs, where the slabs are suitably tied to a neighboring slab without the use of plaster or the like, yet which construction can be readily dismantled without undue injury to the slabs themselves.

Another important object of the invention is the provision of a building construction including slabs with reinforcements therein, which reinforcements may be utilized as a tying or doweling means between slabs.

Another important object of the invention is the provision of a building construction such as a wall or the like using mullions extending preferably the full height of the wall, with shorter precast slabs between mullions, all being tied together by doweling means initially cast into the slabs.

Another important object of the invention is the provision of a building construction involving such mullions and filler slabs where each is complementarily tongued and grooved so as not only to facilitate alignment during erection, but to serve to prevent lateral displacement of the individual slabs with relation to the others.

To this end, the invention in its broadest aspect, contemplates a building construction made of precast slabs wherein those slabs have cast therein during their manufacture metallic reinforcements of such a nature that when the cementitious material of which the slab is made sets, there will be more or less of a bond between the metal element and the material of the slab body. It is preferable that such slabs be tongued and grooved along opposite longitudinal edges so as to insure alignment during assembly or erection.

The invention also contemplates the use of mullions, that is, slabs comparatively long as to their width and, where used in a wall, extending substantially the entire distance between the floor and ceiling, with shorter filler slabs located therebetween. The invention also contemplates the use of longitudinal reinforcements embedded within the mullions inasmuch as these longer slabs are relied upon to lend rigidity to a wall containing them. In some instances, the invention contemplates the interengagement of the lateral and longitudinal reinforcements such as

penetration of the latter by the former. Such a construction is of particular advantage in the molding operation, because the one reinforcement properly locates and supports the other during the casting and setting period.

The invention further contemplates the novel combination, construction and arrangement of parts more fully hereinafter described and shown in the accompanying drawings.

In the drawings—

Fig. 1 illustrates a wall constructed according to this invention;

Fig. 2 is a sectional view along the line 2—2 of Fig. 1; and

Fig. 3 is a perspective view of a wall showing its manner of erection.

Referring now more particularly to the embodiments illustrated, the shorter filler slabs are shown composed of a cementitious body material of any desired material which will hold its form upon setting, compression, baking or the like, and with or without admixtures and fillers such as wood chips, or the like. It is provided on one longitudinal edge with a tongue 2 and on the opposite edge with a corresponding and complementary groove 3. While the tongues and grooves here illustrated are shown as consisting of truncated wedges, yet obviously they may be surfaces of revolution. This tongued and grooved interengagement assists materially in aligning the several slabs during erection.

Cast within the slab at the time of manufacture are a series of lateral reinforcements 4 preferably of an extent co-extensive with or equal to the lateral width of a slab so that the ends of the reinforcements are discernible and accessible at or near the edges of the slabs. For instance, the ends of the reinforcements 4 are clearly shown within the groove 3 in Fig. 3. Obviously any number of these reinforcements may be used, dependent upon the dimensions of the slab 1.

Similarly, longer and narrower slabs 5 may be formed with similar lateral reinforcements therein and these longer, narrower slabs may be used as mullions. In such event, it is desirable to provide longitudinal reinforcements 6 which in this case may be channel irons also cast in the slab at the time of manufacture. Where the lateral reinforcement 4 penetrates the longitudinal reinforcement 6, a particularly desirable condition exists during the casting operation, inasmuch as this engagement definitely locates these parts and prevents juxtaposition during that operation. A particularly rigid structure results after the cementitious material has set. These

mullions 5 are preferably made of a length equal to the height of the wall to be erected and of a width to suit the circumstances. It is desirable, of course, that the total weight of a slab be such that it may be readily handled by two men and such is the case with the mullions of Fig. 3. They are, therefore, considerably narrower than the filler or intermediate slabs 1.

In erecting a wall, for instance as that shown in Fig. 3, a mullion 5 is placed against the wall 1 already erected, a nail punch or the like is placed against the exposed end of the reinforcing dowel 4 and struck a blow to drive the dowel partially out of the mullion and into the wall 1, such as is shown at the left hand end of Fig. 2.

Experiments have conclusively demonstrated that these reinforcements may consist of metal rods placed in the slab during the molding operation and that the bond between the slab body and the reinforcement is not so great that it cannot be broken during the driving out operation without injury to the slab itself. This bond may be decreased to the desired extent by dipping the dowels in oil or the like prior to casting the cementitious material therearound. In any event, when the initial bond is broken, there is still sufficient frictional engagement between the slab and the reinforcement to prevent accidental separation of the two.

After mullion 5 has been secured to wall 1, a light wood wedge may be driven between the end of the mullion and either the floor or ceiling to prevent accidental movement thereof. This will not, in any event, detract from the appearance of the finished wall, because such wedge, the space on each side thereof and even the face of the slabs, may then be given a light coat of plaster to hide the same.

The mullion 5 having been securely put in place, a filler slab 1a may then be located thereagainst and the dowels therein partially driven therethrough into the mullion. This may then be repeated for filler slabs 1b and 1c with the result that this section of the wall is not only secured in place by the tongued and grooved edges, but all parts thereof are doweled together.

If openings such as a window are desired in the wall, a metal frame 8 may then be made to rest upon the filler slabs 1a, 1b, and 1c, the vertical portion of the frame 8 abutting and overlapping the lateral edge of the mullion 5.

Additional filler slabs 1 may then be placed above the frame 8 and secured between the ceiling and the frame 8 by wedges and also to the previously erected slab by partially driving the dowels thereinto. In this way, a complete wall may be erected.

It is desirable that mullions be placed at regular intervals between a series of filler slabs in order to lend the necessary rigidity to the wall as a whole. The frequency with which such mullions occur will, of course, be dependent upon the height, extent and thickness of the wall, and the degree of rigidity desired.

Obviously, door frames 9 may likewise be incorporated into the wall in much the same manner as the window frames 8.

When the end of the wall is reached, it may be necessary to cut one or more slabs longitudi-

nally to fit the remaining space. Such a situation is shown at the right hand end of Fig. 1. In this case, the dowels are first completely removed from the slab and then the slab sawed lengthwise to create a slab of the desired width.

The slabs above the door or window frames may be cut laterally to fit that space without difficulty due to the fact that they contain no longitudinal reinforcements.

The above system provides a very efficient and standardized method of construction, particularly where the door and window frames are made in widths which are multiples of the slab widths.

The slabs may be staggered as with a break joint arrangement or not as desired.

In dismantling or moving a wall of the type illustrated, it is simply necessary to break out the cut slabs at the extreme right hand end shown in Fig. 1, whereupon the remaining slabs may be readily pulled apart, the dowels driven back in place and the entire wall reassembled in some other location. This type of slab has, therefore, a particularly high salvage value.

The entire wall may, after erection, be provided with any suitable type of finish such as paint, plaster, paper or any combination.

While the invention has been shown and described with particular reference to certain embodiments, yet these embodiments are for the purpose of illustration only, and the invention is not to be limited thereto but is to be construed broadly and restricted only by the scope of the claims.

We claim:

1. A wall construction extending between the floor and ceiling comprising spaced apart mullions extending the full height of the wall, each mullion comprising a precast slab having longitudinal and lateral reinforcements therein, opening frames carried between mullions and resting upon filler slabs shorter than the mullions, the filler slabs having lateral reinforcements therein, some of the lateral reinforcements of the mullions extending into the filler slabs and vice versa.

2. The wall of claim 1 in which both mullions and filler slabs are tongued and grooved together.

3. A wall construction extending between a floor and ceiling, comprising spaced apart mullions extending substantially the full height of the wall, each comprising a precast slab having a lateral reinforcement therein, shorter filler slabs located between the mullions, each of said filler slabs having a lateral reinforcement therein, a lateral reinforcement of one mullion extending into one filler slab and vice versa.

4. A building construction comprising a series of precast slabs tongued and grooved together, at least two slabs being longer than the others, each of said longer slabs having an internal longitudinal reinforcement, the shorter slabs being arranged in a series of rows between the longer slabs, all slabs having lateral reinforcements, said reinforcements of the longer slabs entering the shorter slabs and vice versa.
